Specification for Design.

Patented Jan. 6, 1914.

Application filed November 7, 1913. Serial No. 799,824. Term of patent 3½ years.

To all whom it may concern:

Be it known that I, JOSEF DORNBUSCH, a subject of King of Prussia, and a resident of the city of Crefeld, Germany, and whose post-office address is 38 Mariannenstr., have invented a new and original and ornamental Design for Textile Fabrics, of which the following is a specification, reference being had to the accompanying drawing, forming part thereof.

The figure is a plan view of a portion of the textile fabric, showing my new design.

I claim:

The ornamental design for a textile fabric, as shown.

Signed at the city of Aix-la-Chapelle, Germany, this 10 day of October 1913.

JOSEF DORNBUSCH.
